G. H. ROLFES,
LAMP AND METHOD OF MAKING BASES THEREFOR.
APPLICATION FILED OCT. 7, 1920.

1,427,126.

Patented Aug. 29, 1922.

UNITED STATES PATENT OFFICE.

GEORGE H. ROLFES, OF ST. LOUIS, MISSOURI, ASSIGNOR TO HANDLAN-BUCK MANUFACTURING COMPANY, OF ST. LOUIS, MISSOURI, A CORPORATION OF MISSOURI.

LAMP AND METHOD OF MAKING BASES THEREFOR.

1,427,126.

Specification of Letters Patent. Patented Aug. 29, 1922.

Application filed October 7, 1920. Serial No. 415,354.

To all whom it may concern:

Be it known that I, GEORGE H. ROLFES, a citizen of the United States of America, a resident of the city of St. Louis, in the 5 State of Missouri, have invented certain new and useful Improvements in Lamps and Methods of Making Bases Therefor, of which the following is a full, clear, and exact description, reference being had to the 10 accompanying drawings, forming a part of this specification.

This invention relates to improvements in the manufacture of lamps and especially to a lamp having a base provided with a 15 socket for the reception of a supporting staff. The main object of the invention is to provide a simple and inexpensive means whereby lamps of this kind can be adapted to accurately fit the lamp-supporting staffs.

20 Prior to this invention, switch lamps, and some other lamps used in connection with railroad signals, have been supported by rotary staffs, and these lamps should be firmly supported in true vertical positions.

25 The supporting staff is usually provided with a tapered upper end, non-circular in cross section, and the lamp base has a socket in which the tapered end of the staff is inserted. It is economical to make the lamp

30 base of ordinary cast iron, or malleable iron, but such castings are not accurate enough to properly fit the lamp supporting staffs. Heretofore it has been necessary to accurately finish the castings for the purpose of 35 making the sockets conform to the tapering staffs, and lamp manufacturers have carried in stock numerous different castings adapted to be machined and otherwise finished to fit supporting staffs of different dimensions.

40 The cost of the labor involved in finishing these castings is an important item, and it has been very difficult to obtain the desired accuracy in finishing the staff-receiving sockets. The socket should firmly engage 45 the tapered end of the supporting staff, so as to provide a firm support for the lamp, and the lamp should be supported in a true vertical position parallel with the axis of the staff.

50 In accordance with the present invention, the lamp base may be an ordinary rough casting and it is not necessary to smooth the inner surfaces of the staff-receiving socket in the rough casting. In fact, an advantage 55 is gained by leaving these surfaces in a

rough condition. Furthermore, the same pattern may be used in making base castings intended to receive supporting staffs of different dimensions, so it is not necessary for the lamp manufacturer to carry a large 60 stock of different base castings.

Briefly stated, the lamp base may be an ordinary rough casting provided with a tubular mold member which may have rough 65 inner faces. A smooth metal core, conforming to the shape and dimensions of any selected lamp-supporting staff, is inserted into the tubular mold member, and the space between the core and the inner faces of the mold member is then filled by a body of 70 molten metal. When this body of metal becomes cool and hard, it will be interlocked with the rough inner faces of the mold member which forms part of the lamp base, and the entire base can be easily withdrawn from 75 the smooth tapering metal core. The resultant product is a lamp base having a staff receiving socket conforming precisely to the shape and dimensions of the upper end of the staff.

Fig. I is a side elevation, partly in section, illustrating a switch lamp embodying the features of this invention.

Fig. II is an enlarged vertical section 85 illustrating the method of forming the adapter in the lamp base.

Fig. III is a top or plan view of the elements shown in Fig. II.

A designates the body of a switch lamp including a housing 1 provided with a bottom wall 2. B designates a base arranged below and secured to the lamp body.

The base B includes a central tubular mold member 3 non-circular in cross-section, arms 4 extending from the upper portion of said mold member, and supporting wings 5 extending from the corners of the mold member. The lower edges of wings 5 are preferably flush with the lower edges of the mold member 3, so as to allow the lamp to be seated on a horizontal surface when it is not in use. The arms 4 lie within the housing 1 at points below the bottom wall 2, and said arms are secured to the housing 90 by means of rivets 6.

The lamp base, including the mold member 3, may be made of ordinary cast iron, or malleable iron, and the opening in the tubular mold member may be larger at the top than at the bottom of the base casting. 110

C designates a tubular adapter located in the mold member 3 and provided with a non-circular tapering opening conforming to the upper end of a central supporting staff D. This staff D may be considered as the rotatable staff of a railway switch stand.

In Figs. II and III I have illustrated a method of making the adapter C. 7 designates a table on which the lamp base B is seated, and D' designates a metal core located in the mold member 3 of the lamp base and provided at its lower end with a circular head 8 which lies within the table 7. Centering lugs 9 are secured to the table 7 at points on opposite sides of the core D'. These lugs 9 are adapted to engage the wings 5 and mold member 3, as shown in the drawings, so as to enable the base casting 20 to be easily located in the proper position on the table 7.

To form the adapter C, molten metal is poured into the mold member 3 while the core D' is positioned as shown in Figs. II and III. When this metal becomes hard, the lamp base can be very easily withdrawn from the smooth tapering metal core D'. This core conforms to the taper of the supporting staff D, so the smooth inner face 30 of the adapter will accurately fit the supporting staff. The outer face 10 of the adapter C is in direct contact with the rough walls 11 of the mold member 3, so the adapter is securely interlocked with the various projections and other irregularities on the rough inner face of the mold member.

I claim:

1. A lamp comprising a body, a base se-

cured to said body, said base being provided with a mold member, a hollow adapter 40 comprising a metal core cast in said mold member, the outer face of said adapter being in direct contact with the walls of said mold member so as to secure the adapter thereto, and said adapter being provided 45 with an opening for the reception of a lamp supporting member.

2. A lamp comprising a body, a base arranged below and secured to said body, said base including a tubular mold member non-circular in cross-section, and a tubular adapter comprising a hollow metal core cast in said mold member, the outer face of said tubular adapter being in direct contact with the walls of said mold member so as to secure the adapter in the mold member, and said adapter being provided with a non-circular tapering opening for the reception 55 of a lamp supporting staff.

3. A lamp comprising a lamp body, a base 60 below said body, said base including a central tubular mold member non-circular in cross-section, arms extending from the upper portion of said mold member and secured to said body, supporting wings extending from the lower portion of said central mold member and a metallic tubular adapter cast in said mold member, the outer face of said tubular adapter being in direct contact with the walls of said mold member, 65 and said adapter being provided with a non-circular tapering opening for the reception 70 of a central supporting staff.

In testimony that I claim the foregoing I hereunto affix my signature.

GEORGE H. ROLFES,
